BY

ATTORNEY

UNITED STATES PATENT OFFICE.

BERNARD D. HELLER, OF NEW YORK, N. Y.

WINDOW-VENTILATOR.

1,287,306.

Specification of Letters Patent. Patented Dec. 10, 1918.

Application filed August 22, 1917. Serial No. 187,652.

To all whom it may concern:

Be it known that I, BERNARD D. HELLER, a citizen of the United States, residing at New York, in the county of New York and 5 State of New York, have invented certain new and useful Improvements in Window-Ventilators, of which the following is a specification.

My invention relates to new and useful 10 improvements in a ventilator and more particularly to a window ventilator.

The primary object of the invention is the provision of a ventilator adapted to be connected to the window frame whereby the 15 lower sash may be raised and the air entering therebeneath directed upwardly.

A further object is the provision of guide members connected to the frame and a detachable plate received in said guide and 20 extending across the frame.

Another object is the provision of springs within the guide members whereby the plate will be securely held in position and prevented from rattling.

25 With these and other objects in view, the invention consists in the novel details of construction and arrangement of parts which will be more clearly understood from the following description and drawing, in which—

30 Figure 1 is a front elevation showing my ventilator in position with parts broken away to show the manner of connecting the guide to the window frame.

Fig. 2 is a vertical section, and

35 Fig. 3 is a detail perspective of one of the guides.

In the drawings the numeral 1 indicates a window frame of ordinary construction and 2 the lower sash slideable therein.

40 My ventilator comprises guide members connected to the frame and a plate adapted to be received in the guide members. These guides comprise the plate 3 having a plurality of vertically spaced openings 4 and arms 5 extending at right angles thereto. A spring plate is secured on the inner side of one 45 of the arms 5 and comprises a flat portion 6 secured to the arms 5 by means of a rivet 7, an arched extension 8 and the curved portion 9 engaging the arm 5. While I have

described one of the spring plates being attached to only one of the arms 5 it will be understood that a spring plate might equally as well be connected to each of the arms. A 55 plate 10, preferably of glass, extends across

the window frame and has its ends engaged in the guides between the arms 5, and one face of the plate will be engaged by the springs, more particularly the arched portion 8, thereof. The curved portion 9 of 60 the springs bearing against the plate 3 will allow the arched portion to be depressed when the plate is being inserted.

Having fully described the detailed construction it is thought that the manner of 65 using and the advantages will be clearly understood. As above stated one of the guide members is secured to each side of the window frame and the glass 10 is inserted therein with the spring plates bearing 70 against one face thereof. It will be noted that when the glass plate is in the guides the spring plates will hold it against rattling. With a ventilator, such as I have described, the lower sash of the window may 75 be raised as high as the ventilator and the air which comes in beneath the sash will be directed upwardly and will not form a direct draft. At the same time dust entering beneath the sash will be blown against 80 the ventilator and most of the same will lodge upon the window sill, and prevent it entering a room.

Having fully described my invention what I claim as new and desire to secure by Letters Patent is:—

A window ventilating device comprising a pair of metallic strips bent into U shape in cross section and each having openings in its bight portion to receive retaining 90 screws, the said strips being secured to the sides of a window frame with their open sides toward each other, the arms of said strips being parallel, a leaf spring secured at one end in each strip upon one of the 95 said arms near the top thereof, an outwardly bowed portion on each spring intermediate the ends thereof and extending toward the opposite arm, the free ends of said springs being rounded and resting upon the arm to 100 which the spring is secured, and a plate confined at its ends in the strips on the opposite sides of said window frame and being engaged upon its inner face by said springs.

In testimony whereof I affix my signature 105 in presence of two witnesses.

BERNARD D. HELLER.
